FOUNTAIN PEN INK FEED

Ernst O. Weigel, Sr., Irvington, N. J., assignor to
E. O. Weigel & Sons, Newark, N. J.

Application June 27, 1939, Serial No. 281,389

7 Claims. (Cl. 120—51)

This invention relates to improvements in fountain pens, and more particularly relates to vent and ink feed means for fountain pens.

The principal object of the invention is the provision of improvements in a fountain pen whereby to assure a proper flow of ink while writing with the pen.

Another object is the provision in a fountain pen of a simple and practical ink feed means 10 which will keep the pen ready for writing without unnecessary prior manipulations to get the ink to flow to the nib, and which continuously feeds the ink as the result of a positive pumping action set up by the mere act of writing with the pen 15 in the usual manner.

A further object is the provision in a fountain pen of means which affords a nib vent and a forced ink feed, the latter feature being derived as the result of the flexing of the pen nib 20 while writing with the pen in the usual manner.

A still further object is the provision of an inexpensive ink feeding means in a fountain pen which makes it a more satisfactory writing instrument.

25 The nature of the invention and its distinguishing features and advantages will appear when the following specification is read in connection with the accompanying drawing, in which:

Figure 1 is a top view of the writing end of a 30 fountain pen embodying the present invention.

Fig. 2 is a longitudinal section taken on the line 2—2 of Fig. 1.

Fig. 3 is a section showing the nib flexed as 35 occurs when writing with the pen, and also showing ink in the passage of the feed.

Fig. 4 is a view similar to Fig. 3, but showing displacement of some of the ink out of the feed 40 passage and onto the nib caused by reflex of the nib to a normal disposition.

In the drawing there is shown on an enlarged 45 scale the writing portion of a conventional fountain pen. Referring now more particularly for the details of the invention it will be apparent that the parts of the pen shown consist of a barrel 10 with a detachable end section 11 and connected fount or bladder 12 for the writing fluid or ink. An ink feed 13 and nib 14 in association with each other fit tightly in the bore of

50 the section 11 which communicates with the interior of the bladder 12. The nib 14 may be of any type or style and be made of any suitable material or combination of materials, such as gold, steel, etc. The nib 14 has the usual slit 15. The feed 13 has the usual longitudinally disposed

fissured ink passage 16 whose inner end communicates with the bore in section 11 and whose outer end terminates short of the outer extremity of the feed 13. Thus ink may flow from the bladder into the passage 16. The nib 14 has therethrough at or rear the end of the slit 15 a hole 5 which admits air to the bladder through the passage 16 and bore of the end section so that the ink may flow out of the bladder in accordance with the usual practice.

In accordance with the invention use is made of a piece of tubular stock of any suitable material such as metal, Celluloid or other malleable material. This piece of material is positioned in the aforesaid air hole and by means of a die press or other appropriate device said piece is developed or upstruck into an eyelet 17 securely attached to the nib 14. The eyelet 17 preserves the usual vent and also provides means on the nib 14 consisting of a protuberance or projection 18 juxtaposed with respect to the passage 16 between the ends thereof. The protuberance 18 approximates the depth and width of the passage in order to act as a plunger in conjunction therewith. The protuberance moves into and out of the passage 16 as the nib 14 is flexed in opposite directions in writing with the pen in the usual manner. This augments or causes the flow of ink from the passage to the nib since there is set up a positive pumping action. The displacement of ink by the protuberance 18 takes place when the nib flexes toward the feed 13, and normal flow of the ink is possible when the nib flexes away from the feed 13. The ink in being displaced by the protuberance 18 will pass or stream along the line of least resistance toward the point of the nib. Consequently there is a continuous supply of ink furnished to the nib. The means 18 also acts as a valve member or stop to retain some of the ink in the outlet end portion of the passage 16 by preventing return flow thereof when the nib is normally unflexed while the pen is not in use. This will keep the pen ready and primed for writing the instant the nib is brought into contact with the writing paper without unnecessary prior manipulations, shaking and coaxing.

It will be obvious that in attaching the means 18 coincidental with the usual air hole in the 50 nib that the essential venting feature of the pen is preserved. It is to be understood however that the means 18 may be employed in conjunction with the nib and feed passage of the pen in any other way in which the result looked 55

for may be attained without departing from the spirit of the invention, the scope of which is set forth in the appended claims.

What is claimed is:

- 5 1. In a fountain pen, a feed having an ink passage therein, and a nib having means which is movable into and out of said passage to augment the flow of ink from the passage to the nib when flexing the nib while writing with the pen in the usual manner, said means having a vent to supply air to the fount of the pen.
- 10 2. In a fountain pen, a feed having an ink passage therein, and a nib having means which sets up a pumping action in conjunction with said passage to augment the flow of ink from the latter to the nib when flexing the nib while writing with the pen in the usual manner, said means having a vent to supply air to the fount of the pen.
- 15 3. In a fountain pen, a feed having an ink fissure therein, and a nib having a protuberance approximating the depth and width of said fissure, said protuberance being movable into and out of said fissure to augment the flow of ink from the fissure to the nib when flexing the nib while writing with the pen in the usual manner.
- 20 4. In a fountain pen, a feed having an ink fissure therein, and a nib having an element consisting of an eyelet providing a vent and also means movable into and out of said fissure to

cause the flow of ink by displacement from the fissure to the nib when flexing the nib while writing with the pen in the usual manner.

5 5. In a fountain pen, an ink feed, a nib, and cooperative means consisting of a longitudinal ink fissure in said feed and an eyelet-like member on said nib to cause the flow of ink by a positive pumping action to the nib when flexing the nib in writing with the pen in the usual manner.

10 6. In a fountain pen, a feed having an ink passage therein, a nib, and a part which extends through the nib and the material of which is upstruck to secure said part to the nib, said part being movable into and out of said passage to augment the flow of ink from said passage to 15 said nib when flexing the nib while writing with the pen in the usual manner, said means also serving to retain some of the ink in the outlet end of the passage by preventing the return flow thereof when the pen is not in use.

15 7. In a fountain pen, a feed having an ink fissure therein, a nib, and an element which extends through said nib and the material of which is upstruck to secure said element to the nib thus providing a vent and also means movable 25 into and out of said fissure to cause the flow of ink by displacement from the fissure to the nib when flexing the nib while writing with the pen in the usual manner.
